OVERCURRENT PROTECTIVE DEVICE

Ralph R. Pittman, Pine Bluff, Ark.

Application June 15, 1933, Serial No. 675,944

3 Claims. (Cl. 200—127)

This invention relates generally to devices adapted for disconnecting an electric circuit from a source of energy upon the passage of a predetermined current through the circuit, and particularly to that type of fusible devices commonly referred to as expulsion fuses.

I am aware that many types of expulsion fuses are in general use at this time, but, so far as I have been able to discover, all of these devices comprise a hollow tube of insulating material and means forming an arc within the tube, the material of the tube usually being adapted for volatilizing upon the occurrence of an arc therein. It has been found that such a device has a definite minimum current value below which the device will not properly operate to extinguish the arc within the tube, this value depending upon the proximity of the arc path to the bounding surfaces, and the material used in the construction of the tube. It has also been found that such a device has a definite maximum value above which the tube walls are ruptured, this value depending particularly upon the cross-sectional area of the opening, or arc path, through the tube.

The object of the present improvement is to provide a device which will operate properly over a much greater range of current values than that of previous devices of this general type, by providing means for maintaining the arc path in intimate association with the bounding surfaces, but at the same time providing ample cross-sectional area through the arc path to prevent excessive gas pressure.

A further object is the provision of a simple, effective and relatively inexpensive device for the purpose stated.

With the above and other objects in view which will appear as the description proceeds, this invention resides in the novel features of form, construction, arrangement and combination of parts hereinafter described and pointed out in the claims.

In the accompanying drawing (1 sheet) Figure 1 is a side elevational view of a device embodying this invention.

Figure 2 illustrates another elevational view of the device, but here shown in section.

Figure 3 illustrates a sectional view of the device, taken from the plane indicated by the line 3—3 of Fig. 2.

Figure 4 illustrates another sectional view of the device, taken from the plane indicated by the line 4—4 of Fig. 2.

Referring now more in particular to the draw-

ing, it will be seen that the hollow tube 10, of some suitable insulating material, as horn fiber, is provided at the upper end with the metal electrode 12, the latter being rigidly secured to the upper end of the tube 10 by means of cooperating threads on the tube 10 and the electrode 12. An integral portion of the electrode 12 extends upwardly to form the contact surfaces 18, the latter being adapted to engage contact clips of any suitable form. An opening of suitable size 14 is provided at the top of the electrode 12, this portion being also provided with a threaded end to permit the securing of the removable cap 13 by means of cooperating threads on the latter. The electrode 12 is provided with a plurality of inwardly extending portions 21 arranged to form a centrally positioned recess, and an insulating element 11, which may be a horn fiber rod or tube having closed ends, extends upwardly into the recess, and is thereby centrally supported in coaxial relation to the tube 10 at its upper end. The space between the inwardly extending portions 21 permits a communicating passage from the upper end of the electrode 12 to the annular space between the tube 10 and the insulating element 11.

The lower electrode 16 of the device may be constructed of any suitable metal, and is rigidly secured adjacent to the lower end of the tube 10 by means of cooperating threads on the electrode 16 and the tube 10. In a manner similar to that described in connection with the upper cap 12, the insulating element 11 is supported in coaxial relation with the tube 10 at its lower end by the recess formed by the inwardly extending integral portions 22. An integral portion of the lower electrode 16 extends downwardly to form the contact surfaces 18 for engaging contact clips of suitable form. A lower fuse terminal formed by the member 19 and the screw 20 is rigidly attached in any suitable manner to the external upper portion of the electrode 16.

Since in this device, as has long been the practice in the construction of expulsion fuses, the tube 10 and the insulating element 11 may be constructed of insulating material adapted for volatilizing upon the occurrence of an arc adjacent thereto, the lower electrode 16 is provided with the gas vents 17 to prevent the rupture of the device due to excessive pressure within the tube 10.

In installing a fuse link within the device, the cap 13 is removed, and the lower end of the fuse link 14 is urged downwardly through the

110

opening in the electrode 12, the communicating passage between the upper end of the electrode 12 and the annular space formed by the tube 10 and the insulating element 11, the abovementioned annular space, and one of the vent openings 17. The upper button of the fuse link then engages the upper end of the electrode 12, and the cap 13 is screwed thereon to contact the button of the fuse link. The lower end of the fuse link is bent upwardly to engage the member 19, and is rigidly attached thereto by the screw 20. The fusible element 15 of the fuse link is preferably located near the upper end of the insulating tube 10.

15 The insulating element 11 may be of any suitable insulating material adapted to withstand without damage the heat of an arc adjacent thereto, but a preferable material is one having a certain resilience, and which at the same time will 20 evolve gas when placed in intimate association with an arc. Since the fusible element 15 occupies but a small portion of the annular space between the element 11 and the tube 10, the arc will tend to be somewhat localized when first initiated, resulting in a certain impact against the portion of the element 11 adjacent to the fusible element 15. It is desirable therefore to use an element having a certain degree of resilience in order that the cross-sectional area of 25 the arc path may be somewhat controlled by the magnitude of the current in the arc. While it is entirely possible to suspend the element 11 on springs to supply the desired resilience, I prefer, for reasons of simplicity and economy, to employ an insulating element having sufficient inherent resilience to adjust itself to the conditions, and a good quality of horn fiber meets this requirement.

It will be seen from the above description that 40 the fusible element 15 is positioned in the annular space defined by the outer surface of the insulating element 11 and the inner surface of the tube 10, and that, upon the passage of sufficient current through the device, the fusible element 45 15 will be melted, and the circuit-interrupting arc established in the above-mentioned annular space.

It has long been recognized that devices which 50 depend upon the generation of gas within a chamber bounded by insulating material due to the heat of the arc to thereby extinguish it are most effective when the arc is held in intimate relation with the gas-evolving insulating material. For this reason small bore tubes used in 55 expulsion fuses have long been recognized as effective arc extinguishing devices, but the difficulty has been that the cross-sectional area of the arc path in such a device is so small that excessive pressure, tube erosion and flame length 60 make them undesirable for heavy currents.

Recognizing the principle that, for a given cross-sectional area of arc path the effectiveness of arc extinction depends upon the nearness of the arc to the insulating material bounding the arc path, a practical example of the application 65 of this invention will be described.

Assume that a device is required which is effective in extinguishing comparatively low current arcs, and for this reason no portion of the arc 70 path must be removed more than $\frac{1}{8}$ " from the bounding insulating walls. Using a hollow tube, the bore of the tube would be of $\frac{1}{4}$ inch diameter, and the cross-sectional area of the arc path 75 0.04909 square inch. Such a device, because of the small bore, may be fairly effective at currents

up to the order of 200-300 amperes, 60 cycles, but above this range the gas pressure and tube erosion increase rapidly with increased currents, until finally the tube ruptures.

Using the construction here shown, and meeting the same condition, (i. e. that no portion of the arc path be removed more than $\frac{1}{8}$ " from the bounding surfaces) the inside diameter of the tube 10 may be $1\frac{1}{2}$ inches, and the outside diameter of the insulating element 11 one inch, thus providing a $\frac{1}{4}$ inch annular arc space. The condition of proximity of insulation to the arc path has thus been met, but it will be seen that the cross-sectional area of the arc path is that of the annulus defined by the $1\frac{1}{2}$ inch tube and the 1 inch insulating element, which in this case is 0.9817 square inch. This area is substantially twenty times that of the $\frac{1}{4}$ inch bore tube, or approximately equivalent to a tube having a bore of $1\frac{1}{8}$ inches.

The device thus constructed has therefore approximately twenty times the interrupting capacity of a $\frac{1}{4}$ inch bore tube of equivalent wall strength, but at the same time is effective on the low currents above mentioned. A device embodying the arrangement of parts shown herein has, therefore, arc extinguishing properties not to be obtained in the tube, and over a much greater range of current values with a minimum gas pressure and greatly reduced wall erosion.

100 A further advantage of the arrangement shown herein lies in the fact that ample space is provided for the flexible conductors 14, which are used to connect the fusible element 15. This is of especial importance in fuse links above 100 amperes rating, as the connecting conductors must be large in cross section to avoid overheating. In 105 the simple tube device, these elements are of such size that they substantially block the egress of the gases, and thus contribute to the rupturing 110 of the tube walls.

115 While the above constitutes a description of one embodiment of this invention, and to the best of my knowledge a recital of the manner in which the device functions, it is to be understood that such changes as come within the scope of the appended claims may be made without departing from the spirit of the invention. For example, a device according to my invention in which the insulating element 11 is not disposed in exact coaxial relation with the tube 10 would be an effective arc extinguishing structure, although I have herein illustrated and described only the preferred 120 embodiment employing a coaxial arrangement of these elements.

125 I claim as my invention:

1. An expulsion fuse comprising a hollow tube of insulating material, an upper conducting electrode and a lower conducting electrode rigidly fixed on said tube near the respective ends thereof, an inherently resilient cylindrical element of insulating material having an outside diameter less than the inside diameter of said tube supported within said tube by said electrode, means for supporting a fusible element in the annular space between said tube and said insulating element at a position near the upper end of said insulating element, and means including a hemispherical upper end portion of said insulating element engaging a complementary surface on the lower end of said upper electrode whereby, upon the initiation of a circuit-interrupting arc due to the melting of said fusible element, the gas pressure incident thereto may deflect laterally the upper portion of said insulating element for a dis-

tance dependent upon the magnitude of the current in the circuit-interrupting arc.

2. An expulsion fuse comprising a hollow tube of insulating material, conducting electrodes rigidly fixed on said tube near the respective ends thereof, an inherently resilient cylindrical element of insulating material having an outside diameter less than the inside diameter of said tube supported by said electrodes within said tube, 10 a detachably-mounted fuse-engaging member supported on each of said electrodes externally of said tube, and a passageway extending through each of said electrodes in communication with the inside of said hollow tube whereby a fuse link may 15 be supported within said tube independent of said insulating element.

3. An expulsion fuse comprising a hollow tubular insulator, conducting electrodes spaced apart on said insulator near the respective ends thereof, a cylindrical element of insulating material having an outside diameter less than the inside diameter of said insulator supported by said electrodes and extending through said insulator, a detachable fuse-engaging member on each of said electrodes mounted externally of said insulator, and a passageway extending through said electrodes in communication with the inside of said hollow insulator whereby a fuse link may be installed in said fuse without removing said electrodes or said insulating element. 80 85
